UNITED STATES PATENT OFFICE

2,661,160

REVERSIBLE HAMMERMILL WITH POWER-DRIVEN IMPACTOR SURFACES

Edwin H. Keiper, Philadelphia, Pa., assignor to Pennsylvania Crusher Company, Philadelphia, Pa., a corporation of New York

Application October 26, 1951, Serial No. 253,409

2 Claims. (Cl. 241—186)

1
This invention relates to hammermills of the center feed type and particularly to the breaker surfaces on the sides of the entrance chamber.

The object of the invention is to provide a center feed hammermill that effectively crushes both dry and wet material.

Another object of the invention is to provide a center feed hammermill with self-cleaning breaker surfaces.

Another object of the invention is to provide a center feed hammermill with breaker surfaces from which sticky material is removed to fall outside of the crushing zone and drop clear of the breaker surfaces.

A still further object is to provide a center feed hammermill with breaker surfaces that maintain themselves clean of wet sticky material and expel the material from the vicinity of the breaker surfaces so as not to interfere with the operation of the machine.

Other objects and advantages of the invention will appear from the following specification taken in connection with the accompanying drawing in which:

Fig. 1 is a vertical sectional view of a typical embodiment of the invention;

Fig. 2 is an end view diagrammatically illustrating the drives for the rolls; and

Fig. 3 is a fragmentary view of a roll and scraper.

In Fig. 1 a reversible center feed hammermill symmetrical about a vertical plane through the center of the rotor 10 is shown. The rotor 10 has hammers 11 fed with material at the top center of the hammer circle from a feed chute 12. The material is crushed against the breaker surfaces comprising rotating rolls 13, 14, 15 and carried down against the screen bars 16 and passes out of the crusher through the slots 17 between the bars and the opening 24.

An outer casing is provided enclosing the rotor 10, rolls 13, 14, 15 and the screen bars 16. The casing comprises end plates 18 and sides formed by top plates 19, corner plates 20 and side pieces 21 having openings 22 with covers 23. The central feed chute 12 is formed by the flanged plate structure 25 above the top plate 19 and the casting 26 below.

Disks 27 of the rotor 10 are mounted axially along the shaft 28 and pivotally carry the hammers 11. Rows of hammers are thus formed longitudinally of the crusher between the end plates 18. Material drops through the chute 12 and enters the rotor 10 radially at top center.

The hammers 11 fracture the material and drive 55 provided extending longitudinally along the rolls

it against the rolls 13, 14, 15. The material is reflected from the rolls and rebounds for further reduction between the hammers and rolls. The reduction action then passes down between the 5 hammers and the screen bars 16. The plates 29 at an angle across the discharge opening 24 provide a final reduction of the material.

The screen bars 16 are mounted on the supporting beam 31 pivoted at its upper end and having 10 an adjusting mechanism 32 at its lower end. The plates 29 are pivotally supported by pins 33 at their upper ends and adjustably supported by the rods 34 pivotally connected to the lower ends by the flexible joint 35. The opposing anvil plate is drawn back to clear the opening 24. In the case of clockwise rotation the plate on the right side is drawn back and on counterclockwise rotation the plate on the left side is drawn back.

The rolls 13, 14, 15 are mounted on shafts 40, 20 41, 42 respectively carried in bearings in the end plates and are driven by gears 43 from the worms 44. In the gear drive shown, drive shaft 28, through worm gear 45 and clutches 46, drives the rolls on the left side counterclockwise and the 25 rolls on the right side clockwise.

The rolls against which the material is being hit must be turning. The other set of rolls are preferably idle.

The rolls 13, 14, 15 are preferably hollow cylinders with radial disks supporting the rolls concentrically on the shafts 40, 41, 42 respectively. The shafts are set so that adjacent rolls may engage one another but are preferably spaced. Although the rolls may be spaced and have separated surfaces the rolls are so spaced that a substantially continuous anvil surface is presented to the material hit by the hammers and the hit material does not pass through the space between the rolls. The roll 15 is positioned so that the anvil surface of the rolls starts below the hammer circle and continues up on the other rolls 13 and 14 above the hammer circle on the side of the entrance chamber. The rolls may be in separate longitudinal sections so that worn and unworn sections may be interchanged to distribute the wear and lengthen the life of the rolls.

The rolls 13, 14, 15 form impact or breaking surfaces against which the material is hit. Wet or sticky material forms a coating on the breaker surfaces reducing the efficiency of the reducing action. The rolls 13, 14, 15 are turned to move the exposed surfaces of the rolls upwardly and present clean surfaces towards the rotor. On the other side of the rolls, scrapers 48, 49, 50 are provided extending longitudinally along the rolls

13, 14, 15 respectively and remove the material from the surface of the rolls. The scrapers may be pivotally mounted at each end on flanges 51, 52, 53 respectively which are fastened to the end walls 18 by bolts 54. Springs 55, 56, 57 are mounted respectively on the flanges 51, 52, 53 and press against the respective scrapers to resiliently hold them in engagement with the surface of the rolls. The edge of the scraper removes the adhering material from the surface of the roll. The loose material slides over the tops of the scrapers free of the roll. The spaces along the top surfaces of each blade are preferably free of any obstruction to form a continuous open passage or channel 58 between the wall 20 and the roller 13, scraper 48, roller 14 and scraper 49. The passage 58 continues on down between the wall 21 and the scraper 49 and roller 15 into a chamber 63 in back of the screen bars 16. The material removed by the scraper 48 from the roll 13 drops into the passage 58 onto roll 14. The material is then scraped off by scraper 49 from the roll 14 and falls into the passage 18. These scrapings combine with the scrapings from the roll 15 and drop into the chamber 63 clear of the crushing mechanism of the hammer mill and thence out through the opening in the bottom of the casing.

The sticky material does not become adhered to the rolls building up thick layers and is removed from the mechanism so that it is kept clean and operable during long periods.

I claim:

1. A crusher having a rotor carrying hammers, a feed chute terminating vertically above the top of the rotor and providing an entrance space

5

10

15

20

30

35

through which material is freely dropped vertically downward into the top of the hammer circle of the rotor, a movable anvil means having surfaces along one side of said entrance space and extending from an upper point above the top of said hammer circle and at the lower end of said feed chute to a lower point at the downward side of said hammer circle and below the top thereof, driving means for moving said anvil means to carry said surfaces upward over the rotor and upward along the side of said entrance space and tangent to the vertically dropping material in said entrance space to receive the material thrown by said hammers across said entrance space and across the paths of the material entering vertically from the feed chute, and scraping means engaging the surface of the anvil means to remove material adhering thereto.

2. A crusher as set forth in claim 1 in which the movable anvil means comprises a plurality of cylindrical rolls.

EDWIN H. KEIPER.
